UNITED STATES PATENT OFFICE.

WILLIAM GRANT BROWN, OF NEW YORK, N. Y.

PACKAGE FOR MILK.

1,013,639.

Specification of Letters Patent.

Patented Jan. 2, 1912.

Application filed December 17, 1910. Serial No. 597,871.

To all whom it may concern:

Be it known that I, WILLIAM G. BROWN, a citizen of the United States, and resident of New York city, in the county of New 5 York and State of New York, have invented certain new and useful Improvements in Packages for Milk, of which the following is a specification.

My present invention relates to packages 10 for milk, and has special reference to packages which can be utilized not only for temporary storage, but for transportation.

It is well understood in handling milk to be of the utmost importance to keep it as 15 nearly as possible at uniform low temperature, and also to protect it from contamination. No other article of food is so easily spoiled or so dangerous when spoiled, since in most cases it goes to unobservant and 20 often ignorant people who do not know the difference between good and bad; and also, because contamination is often unascertainable without analysis, so that no amount of care on the part of the consumer can prevent 25 risk. Under present conditions the general trade in milk has passed altogether into the hands of a few concerns in each locality, which have sufficient capital to provide the necessary means for transportation 30 and storage. The effect of this is to limit competition and to make it almost impossible for consumers to get milk from other concerns; and, as is well known, to put the farmers or other small dairymen more or less 35 at the mercy of the larger concerns as to the price which they receive. The article being incapable of preservation for any time, the current market price must be taken at once or the value is lost altogether.

40 As at present conducted the transportation of milk is carried on in cars which are artificially cooled. The transportation is done almost altogether at night, and as a consequence a considerable part of the milk 45 is that which has already been kept for twelve hours. Many forms of package have been devised, all of which are so far as I know open to more or less objection. The following requirements of a successful pack- 50 age must, however, be met: First: the milk should be absolutely protected against exposure, not only to contact with any other substance whatever, but the can in which

it is carried must be so hermetically sealed that it will be protected even against odors; 55 since it is well known that these are easily absorbed by milk, and even if they are not injurious are unpleasant to the taste, and often render it unmerchantable. Second: the can must be so securely and completely 60 fastened, and thus protected against being tampered with in transit or at the retailers, that the milk cannot be adulterated or skimmed. Third: the can must be kept at a moderate temperature, as low as possible 65 without freezing the milk. These are essential requirements, and there are other things of less importance which are desirable.

I have devised a package which permits the can to be locked (and sealed also if desired) so that it cannot be opened except by those authorized to do so; and which is also of such a character as to maintain it at an even temperature. The can is also provided with an automatic faucet having a check- 70 valve therein, so arranged that while it is possible to discharge the milk through the faucet it is impossible on account of the presence of the valve to force water into the can therethrough; and the can is provided 75 with an agitator which, whenever any of the milk is removed therefrom, forcibly stirs up all the contents of the can so that the cream and the milk are thoroughly mixed. This latter element of my invention is of the 80 greatest importance in practice, since with all the arrangements which have heretofore been devised and which are within my knowledge, it has been possible to run off the 85 milk and leave the cream or to run off the 90 cream and leave the skimmed milk, which are equally objectionable. The first is accomplished by having a faucet which taps the lower part of the can, which is maintained stationary. As soon as the milk begins to show cream, the dealer ceases to sell 95 it as milk, and sells it as cream at an increased price. It is obvious that the converse would be the case were the faucet so located as to draw off the cream first, the 100 milk being drawn off subsequently by tapping the can. Both of these plans are not uncommon, where not prevented by the authorities. In my improved package, however, it is impossible to remove any part of 105 the contents of the can without tilting it

- from a vertical to a horizontal position, and the operation of my agitating device being dependent upon this shifting of the position of the can, is insured at all times.
- 5 The containing package or box for the can is built preferably with vertical compartments, one of which contains the ice in intimate contact with the can, and the other the can. The box or case is provided with
- 10 bearings by which it may be mounted upon a stand, the arrangement being such that there is a little tendency to maintain the can-end vertical, this tendency being partly counterbalanced by the weight of the ice.
- 15 The can rests upon a partition or grating within the box, by which means the water from the melting ice is free to flow back and forth. With this arrangement, when the box is tilted upon its bearings (which is
- 20 easily accomplished by reason of the counter-balancing referred to) the top of the can containing the faucet, as presently to be explained, becomes the side, and the ice-water collects in what is now the bottom of the
- 25 box. As soon as the dealer lets go of the faucet, however, the can naturally overbalances the weight of the water and the device settles to its upright position, the ice-water flowing back around the can.
- 30 The accompanying drawings show an embodiment of my invention in one form. In them Figure 1 is a conventional perspective, partly broken away, of the ice-chest holding the can. Fig. 2 is a section upon the line
- 35 2—2 of Fig. 3 showing the same parts. Fig. 3 is a side elevation, and Fig. 4 is an end elevation of the parts shown in Fig. 1. Fig. 5 is a section on the line 5—5 of Fig. 6, and Fig. 6 is a side elevation, of the can. Fig. 7
- 40 is a side elevation, partly in section and partly broken away, of a different form of agitator. Figs. 8, 9, and 10 are respectively end and side elevations of another form of agitator. Figs. 11, 12, 13 and 14, show a
- 45 modified construction of the can. Figs. 15 to 18 show a modified form of the agitator of my invention, applied to a milk can of ordinary construction. Fig. 19 shows in section the improved measuring faucet which I
- 50 employ, and Fig. 20 shows the check-valve which is to be used with the faucet. Fig. 21 shows a valve adapted to the package shown in Figs. 22 and 23. Figs. 22 and 23, show a barrel-package embodying the in-
- 55 vention.

In Fig. 1, A is the box, which contains the ice and the can. The ice is contained in the grated receptacle B, provided with a perforated top B¹ having retaining bolts B²,

60 working against a spring B³, the object of this being to prevent the ice sliding about when the box is tilted, as presently to be described. A cover A¹ is secured to the box by slides A² and a hasp A³, so arranged that it

65 is flush with the top of the box so that one

box may be stacked upon another when desired, as when returning empties to the farmer; in general when the cans are full the car has its rated load when they cover the floor.

In Fig. 2 the same parts are shown, except that the top of the box is removed so as to show the top C¹ of the can, more fully to be described presently.

In Figs. 3 and 4, the box A is shown resting upon a stand D, which may be constructed in any desired manner, and is preferably provided with trunnions D¹ D¹, upon which the bearings A⁵ of the box are placed. The lock A⁴ secures the hasp A³, fastening the top of the box in place. Stops A⁶ A⁷ coöperate with the stand to prevent the box being tilted too far. In general the weight of the milk is so great that when the box is released it will fall back until the stop A⁶ comes in contact with the side of the stand; but on account of the weight of the ice counterbalancing a part of the weight of the milk the blow is not sufficiently heavy to be objectionable. The stop A⁷ acts to prevent the can from tilting too far forward.

Figs. 5 and 6 show the can which I may use, having the agitator in place therein. The agitator E is a flat piece of metal or any other material which will stand hot water, and which will not absorb or contaminate the milk. It is in effect a perforated partition in the can, and by preference I secure it to the cover C¹ so that its position relative to the faucet C² is always maintained. In this construction a rubber gasket C³ is interposed between the top part of the can and the top C¹. The agitator E is provided with holes e e at the top and bottom, so that a circulation is initiated in the can every time it is tilted the milk surging back and forth, thus mixing the cream with the milk. It is to be understood that the faucet C² is intended to be inserted in the can when it arrives at the retail store.

Fig. 6 shows the outside can and the peculiar hasp which I prefer to employ, which permits the secure sealing of the can. The hasp C⁵ is provided with an elongated opening C⁶, so that if the can-cover should become somewhat deformed and it be necessary to screw it up very hard, or to increase the thickness of the gasket, the opening in the hasp will still register with the staple. The lock C⁷ secures the hasp in place, and an express seal C⁸ may also be passed through the staple if desired.

In Fig. 7 I show lugs C⁹ C⁹ which are fastened to the cover C¹, in substitution for the lug to which the agitator is riveted as shown in the other figures. These lugs have slots in them so that the agitator may be inserted therein, and will still register in proper position with the faucet C². As indicated in the drawing the perforations, lettered in this

case e^1 e^1 , are elongated into slots, which I find to operate very efficaciously.

Figs. 8, 9, and 10 illustrate the same construction; in this case the agitator is shaped as part of a cylinder, the concavity being toward the faucet. By this construction, when the milk does not reach the top of the can a large air-bubble forms under the agitator (when it is horizontal) in the curved portion, and running back forces its way through the holes e e at the bottom of the can, giving rise to a quite forcible agitation of its contents.

I have illustrated the agitator as fitting closely to an inside diameter of the can; but it is obvious that this fit may be a loose one, as indicated in Fig. 7, and that its sides need not necessarily be parallel with those of the can. In general I find the best effect to be when the agitator is a reasonably close fit, since that insures the circulation which I am to set up, but it may be departed from, as already indicated, without ceasing to employ my invention.

The operation of the arrangement shown, while sufficiently obvious from the foregoing specification and the drawings, is as follows: When the box A is shipped, ice is placed in the ice-box or grating B, the cover A^1 is slipped into place and the lock A^4 secured. Upon arrival at the retail store, the box is placed upon the trunnions D^1 D^1 of the frame D, the lock A^4 is removed by the dealer, and the faucet C^2 inserted in the can. When it is desired to take out the milk the box is tilted into the dotted line position shown in Fig. 3, and when the desired quantity has been removed and the faucet turned off the box is allowed to tilt back to the normal or full line position of Fig. 3. When in the dotted line position, the water and ice lie on the bottom of the box and when tilted back the ice-water rushes back around the can; this insures a circulation of the ice-water and keeps the can chilled so that the heating of the milk is prevented. When the box is to be shipped to the farmer the dealer turns it up and empties out the ice-water, (the ice having melted by this time), restores the cover A^1 to its place, and locks it into position.

In Figs. 11, 12, 13 and 14, I show a modified form of can which is convenient for transportation. As is well known, the present cans have an overhanging top, by means of which they are handled in transportation conveniently, being rolled like a barrel on the bottom edge. With the form of can which I prefer the top is not overlapping, and it is hard to get hold of so heavy an object. I therefore provide a handle H, to which is secured a central bolt h^3 , the lower end of which is formed into or has fixed thereto a circular ratchet h^1 ; a similar ratchet h is secured to the top C^1 of the can,

the bolt passing through it with a loose fit. The handle, as shown in Fig. 11, is arranged with a hinge so that it may lie flat in a depression H^1 formed in the top C^1 of the can. The ratchet is covered by a piece of sheet metal C^{10} secured to the top, so that the milk cannot work out through it; it being designed with all the forms of can which I have devised to seal the milk hermetically therein. The operation of these parts is as follows: When it is desired to move the can, the workman grasps the handle and draws it up so that the ratchet h^1 engages with the ratchet h ; the teeth of these two ratchets are slightly rounded off; when he twists the can to roll it on the lower edge, it is thus unnecessary to release the handle H, the teeth of the ratchets sliding over each other with facility, and the can rolling upon its bottom edge and upon the bolt h^3 . When it is desired to stop the can, however, the handle H is brought up sharply and the teeth of the ratchets will then engage and bring it to a stop. When the can is stood on end and the handle released, it drops into place in the depression H^1 . These figures also show a modified form of joint, in place of the threaded connection between the top and the can which is illustrated in other figures; this is a bayonet joint composed of lugs I^1 I^1 , fastened to the can, and corresponding lugs I I secured to the lid. Co-acting surfaces of these lugs are beveled, and when the lid is twisted it is forced down by the wedge action of these surfaces into close engagement with the can.

In Figs. 15 to 18 I show a form of the agitator which I have devised which is well adapted for use in milk cans of common construction. In such cans it is of course impossible to introduce through the narrow neck an agitator of the full width of the can; and as the neck of the can is often less than half the diameter of the body, it is not expedient to make an agitator which folds only in the middle, as might seem to be the obvious remedy. To accomplish the ends of my invention therefore I arrange the agitator in sections, the central one of which may be withdrawn with the top of the can to which it is secured, and when it is withdrawn the side sections may be collapsed and drawn out of the neck of the can. In Fig. 15 I show the can in section with the complete sectional agitator therein; Fig. 16 shows one of the sections, while Figs. 17 and 18 show in plan and side elevation respectively the central section which holds the other ones in place. As will be observed from Fig. 18, this section is tapered so as to go easily into place and force the others home. The sections upon the right and left are lettered respectively E^1 and E^2 . The central section secured to the can-top is lettered E^3 , and is itself composed of a central

portion to which are secured pieces E^4 , E^5 , which form therewith grooves in which sections E^1 , E^2 are disposed when the device is arranged in the can. In practice the taper 5 of the central section need not be quite so great as is here shown. When it is desired to insert the agitator the parts E^1 , E^2 are placed in the can and adjusted against the lugs C^{11} ; the portion E^3 is then inserted, the 10 edges of the sections E^1 , E^2 being disposed between the plates E^4 , E^5 , whereupon the section E^3 is pressed down firmly into place, forcing out the sections E^1 , E^2 into contact with the sides of the can; this in connection 15 with the curved bottom of the can and the shaping of the diaphragm to fit it, retains the whole in place until the cover is removed and withdrawn. This is not of course so good an arrangement as that in which the 20 agitator is composed of a single sheet which can readily be removed and sterilized, but it is operative and useful.

In Fig. 19 I show in section the measuring faucet which I propose to use. In this 25 J^1 is a glass can having therein a piston J^2 , operated by a rod J^3 , having a handle J^4 and passing through the top J^5 of the can, which is secured thereto by clamps J^8 and has a packing J^9 ; a gland J^6 prevents leakage, and a spring j coöperates with grooves 30 in the rod, so that the correct position for the different measurements indicated by the graduations upon the glass is readily determined. A hollow plug J^{14} is provided 35 with a handle J^{10} and a spout J^{13} ; an opening J^{12} through the plug communicates with the can, and with the milk-can into which the plug is screwed by the threaded nipple K^2 ; while another opening J^{11} , communicates 40 when in the proper position with the can J^1 so that the hollow body of the plug forms a channel between the can and the spout J^{13} . The operation of these parts is as follows: 45 When the handle J^{10} is in the illustrated position, the opening J^{12} permits the milk to flow from the large can into the can J^1 , filling it to whatever capacity the position of the piston J^2 permits; this may be adjusted by the handle J^4 to any of the graduations. 50 A vent J^7 in the top permits the air to enter behind the piston, while the opening in the bottom of the can J^1 with which the channel J^{12} in the plug coöperates, is made funnel-shaped as shown, thus permitting air to 55 flow from the can J^1 into the milk-can. After the milk has filled the can J^1 to the desired capacity, the handle J^{10} is rotated, and the opening J^{12} in the plug is thrown into communication with the can J^1 , the 60 milk from which then flows out through the spout J^{13} ; as the two openings J^{11} , J^{12} are so disposed that they do not register with the entrance ports into the can J^1 at the same time, there can be no flow of milk from the 65 larger can to which the faucet is attached.

without previously turning the handle of the faucet, and thus measuring the discharge.

In Fig. 20 I show a check valve which may be conveniently employed, though other forms may be used, with the faucet just described and which is intended to coöperate with the opening J^{12} . In this, K is the casing and K^1 is a ball which constitutes the valve, K^2 being a threaded nipple, one end 70 of which is formed into a cage which prevents the ball seating so as to cut off the flow of milk; by this arrangement a counter flow of liquid into the can is entirely prevented, as already pointed out, while the 75 openings in the cage K^2 permit the ready outflow of the milk.

Fig. 21 shows the same general character of valve as that of Fig. 20; but this form is adapted for use with the barrel form 80 of package shown in Figs. 22 and 23, presently to be described. In this figure, C^1 is the top of the can, which in this form is provided with lugs c , spacing it away from the top of the package A : An opening a 90 in the package-top is of such size as to permit considerable play, to allow for possible deformation of the tops, or other want of alinement. When the nipple K^2 is inserted it draws up the top C^1 by means of the 95 screw-thread until the lugs engage with the top A , thus holding the can firmly in place.

Figs. 22 and 23 show a barrel-shaped package, the outer vessel L being usually of 100 wood, while the can C may be of metal or glass; the common form of fruit-jar closure, with yoke L^2 and gasket a is used for the outer vessel; and a similar structure, the yoke of which is marked M , for the inner can. An annular ring O , preferably of 105 metal, spaces the two vessels apart, and drops with the melting of the ice; but it does not yield readily to the thrust of the ice as the can is tilted, on account of cramping between the two vessels.

The milk may be shipped in the way pointed out in absolute safety from adulteration or contamination. One of the greatest difficulties which have been met with in enforcing sanitary regulations has been to 115 locate the responsibility for watering milk, or for skimming cream from it. With the package which I have devised, however, no such difficulty arises, because the milk is retailed in precisely the condition in which it leaves the farm or the dealer. If therefore it does not conform to health regulations by being adulterated, or by absence of the proper amount of butter fat, it is at once apparent that the difficulty lies at the dairy-farm and not at the retail store. There are no movable parts in the agitator, and it is as easily kept in a sanitary condition as any part of the can; being removable with the top, it is provided with means for register- 120 125 130

ing with the faucet, in all of the forms which I have indicated. There is no possibility of "beating" it. If the can be turned upon its side the contents will not flow from the 5 faucet; in this case, even though the agitator is turned edgewise and its action is not so efficacious, the circulation not being so violent, nevertheless it will operate, so that the percentage of gain is wholly insufficient 10 to justify the trouble, difficulty, and risk of punishment, of the operation.

Having thus described my invention, what I claim and wish to protect by Letters-Patent of the United States is:

15 1. A package for milk comprising a can, a surrounding receptacle having a space for ice, a support having bearings permitting the rotation of the receptacle, and an agitator in the can brought into action by such 20 rotation.

25 2. A package for milk comprising a can, a surrounding receptacle, a support having bearings permitting the rotation of the receptacle in a vertical plane, the can being located at one side of the axis of rotation so 30 that when it is in its normal position it is substantially vertical and when rotated it is substantially horizontal, and an agitator within the can, brought into action by its rotation.

35 3. The combination of a can with an agitator therein, the agitator consisting of a substantially vertical perforated diaphragm, and bearings permitting the rotation of the can into a substantially horizontal position, the diaphragm when the can is so rotated being in a substantially horizontal plane.

40 4. The combination of a can with an agitator therein, and a faucet in the end of the can, the plane of the agitator being upon a transverse diameter of the can substantially at right angles to the one passing through the faucet; and means for rotating the can upon a horizontal axis in substantially the 45 plane of the diaphragm.

5. The combination of a can having a cover, a faucet adjacent to the edge of the cover, and an agitator secured to the cover on a diameter substantially at right angles 50 to the one passing through the faucet.

6. The combination, in a can, of a cover secured thereto by rotation, an agitator arranged upon substantially a diameter of the cover and rotating therewith, and a faucet 55 in the cover upon a diameter substantially at right angles to the plane of the agitator.

7. The combination of the can, a cover secured thereto by rotation, an agitator therein, means for causing the agitator to register 60 with a diameter of the cover and a faucet in the cover upon a diameter at right angles to the plane of the agitator.

8. The combination of a can and a cover secured thereto by rotation, with an agitator 65 consisting of a perforated diaphragm

registering with a diameter of the cover, a faucet in the cover upon a diameter substantially at right angles to the plane of the agitator, and a hasp upon the cover having an elongated opening so that the cover may be 70 made tight without throwing the hasp out of registry with its staple; whereby the agitator is maintained in a plane at substantially a right angle with the diametral plane of the faucet, while the can may be 75 locked at several positions of the cover.

9. A package for milk comprising a can, a surrounding receptacle, a grating in the receptacle for the reception of ice, and a detaining cover upon the grating; with bearings upon the receptacle permitting its rotation in a vertical plane. 80

10. The combination of a can, a receptacle therefor, a grating within the receptacle for ice, detaining means for preventing movement of the ice, bearings upon the receptacle permitting it to swing in a vertical plane, a cover for the receptacle, and fastening means for the cover arranged flush therewith, so that the top of the package is 90 in substantially a single plane. 85

11. The combination, in a package for milk, of a can and a receptacle therefor, a grated holder for ice within the receptacle, a cover for the holder and spring-actuated 95 bolts upon the cover, with a flush cover for the receptacle and bearings upon the sides thereof permitting its rotation in a vertical plane; whereby the ice-water flows around the can when the latter is in a vertical position, and flows around the ice when the receptacle is rotated. 100

12. The combination, in a package for milk, of a receptacle, a can therein, a holder for ice communicating with the receptacle, and bearings upon the receptacle permitting its rotation in a vertical plane; whereby the ice-water flows around the can when the latter is in a vertical position and when the receptacle is rotated, it flows around the ice, 110 thus being maintained at low temperature and keeping the milk cooled.

13. The combination, with a milk can, of a receptacle therefor, a holder for ice in the receptacle and a cover for the holder secured 115 in place by spring-actuated bolts, the cover being perforated and the bolts so arranged as to permit it to descend to follow the melting of the ice, but preventing it from moving upward; and means for permitting the 120 rotation of the receptacle in a vertical plane; whereby the ice is secured in place and prevented from shifting about, while the water flows around the can when the latter is vertical and around the ice when the receptacle 125 is rotated.

14. The combination of the receptacle, having the can in one side thereof and ice in the other, bearings upon the receptacle permitting its rotation in a vertical plane, 130

a stand upon which it rotates, and stops upon the receptacle, preventing its rotation too far in either direction.

15. The combination of the receptacle, the can and the ice container therein, the stand and bearings permitting the rotation of the receptacle, the bearings so disposed that the can-end of the package overbalances the

ice; and stops upon the receptacle for preventing its over-rotation.

In witness whereof, I have hereunto set my name in the presence of two witnesses.

WILLIAM GRANT BROWN.
